UNITED STATES PATENT OFFICE.

EDUARD ZICKWOLFF, OF SAARBRÜCKEN, ASSIGNOR TO PAUL MÜGEL, OF ST. JOHANN, GERMANY.

PUMP.

SPECIFICATION forming part of Letters Patent No. 450,393, dated April 14, 1891.

Application filed September 25, 1890. Serial No. 366,071. (No model.)

To all whom it may concern:

Be it known that I, EDUARD ZICKWOLFF, a subject of the Emperor of Germany, and resident at Saarbrücken, Germany, have invented 5 new and useful Improvements in Pumps, of which the following is a specification.

My invention relates to the valve-gear and cocks of direct-acting steam-pumps, and also to means for automatically stopping the pump 10 when the water-pressure passes a certain point and starting it again when the pressure falls below that point.

The invention consists of certain novel features of construction and combinations of 15 parts, substantially as hereinafter described and as claimed.

Reference is to be had to the accompanying drawings, forming part of this specification, in which—

20 Figure 1 is a side elevation of a direct-acting steam-pump embodying my improvement. Fig. 2 is a plan view of the same. Fig. 3 is a cross-sectional view on the line *x* *x*, Fig. 1. Fig. 4 is a cross-sectional view on the line *y* *y*, Fig. 1. Figs. 5 and 6 are detail sectional views on lines *v* *v* and *w* *w*, Fig. 4. Fig. 7 is a cross-sectional view similar to Fig. 4, but showing in section the arrangement of the automatic stopping and starting mechanism.

25 30 Like letters of reference designate corresponding parts in the several figures.

A A' designate the aligned cylinders of the pump, B B' the pistons connected by the rod C, and D D' the cylinder-ducts extending 35 from about the middle and along the bottom of each cylinder to opposite ends of the same, the said ducts serving alternately as inlet and outlet ports. The inner ends of each pair of ducts D D' are inclined downward at a right 40 angle to each other and open by ports D³ D⁴ ninety degrees apart through the conical casings E² of cocks E E', arranged transversely across the bottoms of the cylinders A A'.

In each cock-casing E², diametrically opposite each of the ports D³ D⁴, is a pair of separate radial ports F F' and F² F³, of which the ports F F' are connected by a segmental duct G with the induction-pipe G' and the ports F² F³ by a segmental duct G² with the eduction- 45 pipe G³.

The plug E³ of each cock E E' is formed with two transverse ports E⁴ E⁵ at right angles to each other and so adjusted that when the plug E³ is turned so that the plug-port E⁴ will connect the cylinder-port D³ with the 55 port F, and hence with the induction-pipe G', the other plug-port E⁵ will connect the opposite cylinder-port D⁴ with the port F³, and hence with the eduction-pipe G³, and the ports F' and F² will be closed; but when the plug 60 E³ is turned ninety degrees its port E⁴ will connect the opposite end cylinder-port D⁴ with the induction-port F², and its port E⁵ connect the cylinder-port D³ with the eduction-port F', while the ports F and F³ will be closed. 65 The pistons B B', connected by the rod C, will thus be simultaneously reciprocated in the cylinders A A' by the simultaneous operation of the cocks E E'. For thus operating the cocks E E' their plugs E³ are provided with 70 like crank-arms H, which are connected adjustably by long links H' with a segmental rocker I at points equidistant from the center thereof. The rocker I is mounted to turn loosely on a transverse rock-shaft J, which is 75 itself mounted to turn in bearings J', arranged beneath the piston-rod C midway between the cylinders A A'. The rocker I is formed on opposite ends with inward-projecting radial shoulders I', between which is embraced and 80 which are alternately struck by a striker I², which has correspondingly-inclined shoulders and is secured on an arm I³ of the rock-shaft J. The rock-shaft J is also provided with another arm K, carrying an adjustable weight 85 K', and having an inward projection K², provided with opposite radial shoulders K³, which are arranged in the path of and to be struck alternately by the corresponding shoulders 90 of strikers L, formed on opposite ends of the 90 adjacent one of a pair of swinging lever-plates M, so that as said lever-plate M swings to and fro its strikers L will raise and carry the weighted arm K over its center, when it will fall quickly over upon the opposite striker L. 95 Inclined and adjustable abutments N⁶ are arranged to stop the outer end of the arm K at the terminals of its path, and thus take the strain off the strikers L. The lever-plates M swing loosely on the shaft J and are formed 100

with radial slotted guides M' at their outer ends, in which travel friction-rollers M², mounted on a cross-pin M³, carried by the piston-rod C, so that the lever-plates are swung 5 by the reciprocation of the piston-rod C.

The weighted arm K in its peculiar motion, imparted by the lever-plates M and by gravity, as described, likewise rocks the shaft J, and thus the other arm I³, which by its 10 striker I² imparts the same motion to the rocker I, and through the links H' to the cylinder-cocks E E', whereby, owing to the quick ending of the motion, a quick cut-off of the cocks is obtained and the expansion of 15 the steam utilized to its fullest extent.

The segmental rocker I is formed with a medial notch N, adapted for engagement by the latch end O' of an angle-lever O, the other arm O² of which is engaged by a pin O³, carried by the elastic diaphragmic wall of a 20 closed chamber P in communication with the water under pressure, so that the expansion of said wall, due to an excess of water-pressure, will cause the latch end of the angle-lever O to engage the notch N in the rocker I and lock the rocker I, and hence the cocks E E', rock-shaft J, and weighted arm K, midway 25 of its stroke and stopping the pump.

The latch-arm of the angle-lever O is linked 30 to one arm of a fulcrumed lever P, the other arm of which carries an adjustable weight P' in opposition to the pressure on the diaphragmic wall of the water-chamber P, so that the pump can be adjusted to stop when 35 the water-pressure reaches any given point, and when the pressure falls below that point

the latch end of the angle-lever O will be raised, releasing the rocker I, cocks E E', shaft J, and weighted arm K, and thus, as the arm K will then immediately fall over and operate 40 the rocker I and cocks E E', starting the pump.

I claim as my invention—

1. In valve-operating mechanism for pumps, the combination, substantially as hereinbefore set forth, with the piston-rod, the shaft 45 J, the rocking lever M, carrying strikers L, operated by the piston-rod, and the weighted swinging arm K, fast on the shaft J and having striking shoulders K³, of an arm I³, also fast on the shaft J and carrying a striker I², 50 a lever I, rocking loosely on the shaft J and having radial striking-shoulders I' arranged to be alternately struck by the striker I² on the rocking lever I, and operating connections between the rocking lever I and the 55 valves.

2. The combination, with the valves and the valve-operating rocker or lever I, having a notch N, of a latch O', a pressure-chamber P, having a diaphragmic wall, operating connections between said wall and the latch, and a weight acting on the latch in opposition to the pressure, substantially as hereinbefore set forth.

In testimony whereof I have signed my 65 name to this specification in the presence of two subscribing witnesses.

EDUARD ZICKWOLFF.
